MULTIPLE SEATING UNIT

Phillip K. Raiford, Memphis, Tenn., assignor to Shoe House, Inc., Memphis, Tenn., a corporation of Tennessee

Filed Oct. 21, 1965, Ser. No. 87,715

Term of patent 14 years

(Cl. D15—8)

FIG. 1

FIG. 3

FIG. 1 is a perspective view of a multiple seating unit showing my design.

FIG. 2 is an elevational view showing the side opposite that disclosed in FIGURE 1.

FIG. 3 is a plan view thereof.

I claim:

The ornamental design for a multiple seating unit, as shown.
